DESIGN FOR A TABLE OR SIMILAR ARTICLE

Elizabeth R. Butzner, New York, N. Y.

Application March 11, 1939, Serial No. 83,523

Term of patent 3½ years

To all whom it may concern:

Be it known that I, Elizabeth R. Butzner, a citizen of the United States, residing in New York, county of New York, State of New York, have invented a new, original, and ornamental Design for a Table or Similar Article, of which the following is a specification, reference being had to the accompanying drawing, forming a part thereof.

Fig. 1 is a perspective view of the table or similar article showing my new design; and

Fig. 2 is a bottom plan view of the table or similar article illustrated in Fig. 1.

I claim:

The ornamental design for a table or similar article, substantially as shown.

ELIZABETH R. BUTZNER.
